UNITED STATES PATENT OFFICE.

GRANT E. MANN, OF LANGFORD, SOUTH DAKOTA.

RAIL-BRAKE FOR RAILWAY-CARS.

1,279,568.

Specification of Letters Patent. Patented Sept. 24, 1918.

Application filed March 21, 1917. Serial No. 156,424.

To all whom it may concern:

Be it known that I, GRANT E. MANN, a citizen of the United States, residing at Langford, in the county of Marshall and 5 State of South Dakota, have invented certain new and useful Improvements in Rail-Brakes for Railway-Cars, of which the following is a specification.

This invention relates to improvements 10 in railway car brakes, and more particularly to rail brakes.

The object of the invention is to construct an auxiliary safety brake for use in connection with the usual wheel brakes and which 15 is intended to frictionally engage the rails of the track and thereby exert a drag on the car and by means of which the car may be quickly stopped without danger of sliding the wheels and flattening the treads 20 thereof.

Another object is to provide a brake of this character which may be readily applied to cars already in use without any change being made therein and which is automatically applied by the application of the 25 air brake rod.

Another object is to provide a brake of this character in which the braking force may be varied to meet the requirements of 30 the car.

With the foregoing and other objects in view, which will appear as the description proceeds, the invention resides in the combination and arrangement of parts and in 35

the details of construction hereinafter described and claimed, it being understood that changes in the precise embodiment of the invention herein disclosed may be made within the scope of what is claimed without 40 departing from the spirit of the invention.

In the accompanying drawings:

Figure 1 represents a side elevation of a freight car equipped with the improved brakes constituting this invention,

Fig. 2 is an enlarged detail side elevation showing one of the brakes in raised inoperative position,

Fig. 3 is an enlarged horizontal section taken on the line 3—3 of Fig. 2,

Fig. 4 is an enlarged detail vertical longitudinal section through one of the brake shoes,

Fig. 5 is an enlarged detail transverse section taken on the line 5—5 of Fig. 3, and

Fig. 6 is a similar view taken on the line 6—6 of Fig. 4.

In the embodiment illustrated, four brakes embodying this invention are employed, although obviously the number may be varied if found desirable. These brakes, 60 which are preferably arranged in pairs close to the wheels of the car are exactly alike in construction and hence one pair only will be described in detail.

Each pair of brakes, as shown clearly in 65 Figs. 2, 3 and 4, comprises two shoes 1 and 2, constructed in the form shown in Figs. 2 and 4, each shoe having a flat rail engaging face 3 preferably about two feet in length so that the braking surface of the 70 four brakes employed will be about eight feet for each car but of course the sizes of these shoes may be varied as desired.

Each brake shoe has an upstanding boss 4 bifurcated to receive a connecting arm 5, 75 the lower end of said arm being arranged between the furcations 6 of said boss and pivotally connected therewith by a bolt 7, as is shown clearly in Figs. 2 and 4. The opposite ends of each shoe have their lower 80 faces inclined upwardly and bifurcated as shown at 8 and these ends receive supporting braces 9 and 9', the lower ends of which are slotted transversely as shown at 10, and arranged between the furcations 8 of the 85 shoes as is shown clearly in Fig. 4, the slots 10 in said braces 9 and 9' receiving pivot pins 11 and permitting the shoes to move vertically toward and away from the rail R.

A crank shaft 12 connects the two shoes 1 and 2 at opposite sides of the track, the arms 13 thereof being pivotally connected at their free ends with the upper ends of arms 5. A lever 14 is fixed at one end to the cross bar of the crank shaft 12 at a point midway the length thereof, being secured thereto by any suitable or desired means or made integral therewith, as desired. This lever 14 has its upper end bifurcated to straddle an air brake rod 15 and is held in engagement therewith by a bolt 16 passing through the free ends of the furcations of said lever above the rod as is shown clearly in Fig. 2. This lever 14 engages said rod between two clamps 17 and 18 which are adjustably mounted on the brake rod and spaced apart a suitable distance to provide for a predetermined movement of the brake rod before its actuating engagement with lever 14 for raising or lowering the brake shoes. These clamps 17 and 18

are preferably made in the form of split sleeves as shown in Fig. 5 and are secured in adjusted position by means of set screws 19. The collars 17 and 18 between which lever 14 is disposed are spaced apart so as to permit the brake rod 15 to move independently a predetermined distance before it comes into engagement with lever 14 and actuates said lever. The object in so spacing these collars, is that when brake rod 15 is moved the distance of the space between them, it applies the wheel brake, which is used for ordinary stops. If it is desired to stop in a very short space the 10 brake is applied harder and this causes the lever rod 15 to move and come in contact with lever 14 and apply the rail brakes. By so doing, both the rail and wheel brakes are applied. These collars 17 and 18 must be set so as to prevent the wheels from sliding on the rails which would result in flattening of the peripheries thereof and yet the wheel must hold as much as possible without sliding. This provides a greater 20 braking action. Should these collars 17 and 18 not be spaced, the train while traveling slowly as when coming into a station may be brought to a standstill almost instantly and this would result in great wear on the 25 rail brake.

Supporting braces 20 depend from the bottom of the car C and as shown in Fig. 2 are arranged obliquely having bearings 21 at their free ends in which the cross bar 25 of the crank shaft 12 is loosely mounted and is adapted to turn.

The rear braces 9' which support the shoes 1 and 2 are offset laterally inward as shown at 22 in Figs. 2 and 3 to properly position 40 them in relation to the wheels W of the car so that they will not interfere with the operation thereof.

In the operation of this improved rail brake, the parts being in the position shown 45 in Figs. 1 and 2, when brake rod 15 has been moved longitudinally in the direction of the arrow, shown in Fig. 2, a distance sufficient to bring clamp 18 into engagement with the lever 14, it will move said lever rearwardly 50 thereby turning the crank shaft 12 and causing the arms 13 thereof to swing downwardly and through arms or links 5 which connect said crank arms with the shoes to force the shoes 1 and 2 downward into frictional engagement with the rails R at opposite sides of the track. This operation of 55 the rail brakes may occur simultaneously with the application of the wheel brakes according to the adjustment of collars 17 and 18 so that it will not be necessary to exert a full braking pressure on the wheel brakes and thereby prevent said wheels from sliding on the rails which frequently results in the flattening of the treads of the wheels.

60 As hereinbefore described the collars 17 and

18 are preferably spaced apart as shown, to permit the brake rod 15 to move a predetermined distance after applying the wheel brakes before the track brakes are brought into operation.

When the full pressure is applied through means of the brake rods 15, greater force will be exerted on the rail brakes but at the same time the wheel brakes will operate to assist in stopping the car. It is obvious 70 that by the use of these improved rail brakes, four of which are employed on each car, that the train can be brought to a standstill at least four times quicker than can be done without their use and without in any way 75 damaging the car wheels. The use of these rail brakes also prevents all possibility of the wheel brakes sticking, since it is not necessary to apply said brakes with such force as to cause them to stick.

80 If the braking force exerted by the rail brakes is not sufficient it may be increased by lengthening lever 14 and shortening the crank arms 13, which will produce a greater 85 leverage and consequently exert greater 90 pressure of the rail shoes on the rails.

95 From the above description it will be obvious that these improved brakes may be applied quickly and readily to any car already in use having the rail brake rod 15, by 95 simply applying to said rod the clamps 17 and 18, mounting between them the lever 14 and by connecting to the bottom of the car the supporting braces 9 and 9' and 20, all of which may be done without in any way mutilating or injuring the car or necessitating 100 any skilled labor being used.

105 From the foregoing description, taken in connection with the accompanying drawings, the advantages of the construction and of the method of operation will be readily apparent to those skilled in the art to which the invention appertains and while I have 110 described the principle of operation of the invention together with the device which I now consider to be the best embodiment thereof, I desire to have it understood that the device shown is merely illustrative and that such changes may be made as are within 115 the scope of the claimed invention.

I claim:

1. The combination with a car having a longitudinally movable brake rod; of a rail engaging shoe, actuating means for said shoe carried by said rod, and means on said rod 120 to provide for a predetermined movement of the rod before it actuates said shoe.

2. The combination with a car having a longitudinally movable brake rod; of a rail engaging shoe, actuating means for said shoe carried by said rod, and adjustable means on said rod to provide for a predetermined movement of the rod before it actuates said shoe.

3. The combination with a car having a 130

longitudinally movable brake rod; of a pair of laterally spaced rail engaging shoes having upwardly inclined ends, braces depending from said car and having slotted connection with the ends of said shoes, other braces depending from said car, a shaft rotatably mounted in said last mentioned braces and extending transversely of the car, arms extending at right angles from said shaft, 10 links pivotally connecting said arms and shoes, and a lever fixed to said rod and shaft.

4. The combination with a car having a longitudinally movable brake rod; of a pair of laterally spaced rail engaging shoes, 15 braces depending from said car and having

slotted connection with the ends of said shoes, other braces depending from the car, a shaft rotatably mounted in said last mentioned braces and extending transversely of the car, arms extending at right angles from 20 said shaft, links pivotally connecting said arms and shoes, and a lever fixed to said rod and shaft.

In testimony whereof I affix my signature in presence of two witnesses.

GRANT E. MANN.
